(57) **CLAIM**

I claim the ornamental design for a collapsible rifle rack, as shown and described.

DESCRIPTION

FIG. 1 is an isometric view of a collapsible rifle rack in an open configuration showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is an isometric view thereof in a collapsed configuration.

FIG. 9 is a front elevation view thereof.

FIG. 10 is a rear elevation view thereof.

FIG. 11 is a right side elevation view thereof.

FIG. 12 is a left side elevation view thereof.

FIG. 13 is a top plan view thereof; and,

FIG. 14 is a bottom plan view thereof.

The broken lines are for environmental purposes only and form no part of the claimed design.

The claimed collapsible rifle rack can be placed on the floor and used to store rifles in an upright position.
